UNITED STATES PATENT OFFICE.

FREDERICK M. ROSS, OF CINCINNATI, OHIO.

PROJECTILE.

1,276,575.

Specification of Letters Patent. Patented Aug. 20, 1918.

Application filed May 9, 1917. Serial No. 167,418.

To all whom it may concern:

Be it known that I, FREDERICK M. ROSS, a citizen of the United States of America, and resident of Cincinnati, in the county of 5 Hamilton and State of Ohio, have invented a new and useful Improvement in Projectiles, of which the following is a specification.

An object of my invention is to produce 10 an improved projectile of the expanding type adapted for use in the cutting and tearing away of submarine periscopes, air craft guy wires, fighting masts, wireless antennae and barbed wire entanglements.

15 A further object is to produce an improved projectile of the expanding type in which the expansion of the projectile takes place immediately upon its leaving the gun and in which the elements of the projectile 20 are moved to their expanded positions and held therein against collapse.

These and other objects are attained in the projectile described in the following specification and illustrated in the accompanying drawing, in which;

25 Figure 1 is a longitudinal sectional view of a projectile embodying my invention, as applied to shells in which the casing, the charge and the projectile are combined, in 30 the course of manufacture.

Fig. 2 is a somewhat enlarged sectional view of the form of my improved projectile for use in instances where the charge is not carried by the shell.

35 Fig. 3 is a view similar to Fig. 2, but showing the projectile expanded.

Fig. 4 is a transverse sectional view taken on the line 4—4 of Fig. 2 and upon an enlarged scale.

40 Fig. 5 is a transverse sectional view taken upon the line 5—5 of Fig. 2.

Fig. 6 is a detail sectional view of the preferred form of grinding of the blades.

45 My improved projectile consists of a body portion 7, a series of arms 9 which are herein disclosed to be knife blades pivotally mounted at their rear ends and occupying slots 10 within the body of the projectile, and means generally designated by numeral 50 11, for causing the blades to be released by the discharge of the explosive behind the projectile so as to expand upon leaving the muzzle of the gun. In the preferred embodiment disclosed in the drawings, I have 55 provided the body 7 of the projectile with a series of four radial longitudinally ex-

tending slots 10 in each one of which a knife blade 9 is mounted. At the rear end of each knife blade a pin 12 is provided, the pin of each blade occupying an annular 60 groove 13 formed in the body 7. In order to retain the pins within groove 13, I have provided a collar 14 which is slotted at points 15 to fit over the knife blades and to pass each end of each of the pins to confine 65 them to the groove, as disclosed in Figs. 2, 3 and 5. Thus the blades are free to rotate within the groove when they are moved from their contracted to their expanded positions or vice versa. Each blade 9 is pro- 70 vided with a lug 16 which is located on its inner or sharpened edge and which extends to the rear of the projectile when the blades are in their folded positions, as disclosed in Fig. 2, and which extend inwardly toward 75 one another when the blades are moved to their extended positions as disclosed in Fig. 3. Against the rear ends of the knife blades, when they are in their folded positions, one end of a coil spring 17 bears, the 80 opposite end of the spring bearing against a removable cap 18 which is screwed on to the rear end of the body 7 of the projectile. When the blades are in their expanded positions the forward end of spring 17 bears 85 against the edges of lugs 16 of the blades to hold them in their expanded positions as disclosed in Fig. 3. Integrally formed with cap 18 and centrally located with relation thereto is a sleeve 19 adapted to receive the 90 spindle 20 of a releasing plunger or trigger 21, the head 22 of which engages the inner edges of the lugs to hold the blades in their contracted or folded positions, as disclosed in Fig. 2. When in their expanded posi- 95 tions the plunger occupies the position disclosed in Fig. 3. In the construction of my improved projectile I preferably form the body 7 of two sections comprising a portion 7^a in which slots 10 are formed and a head 100 7^b which is secured to portion 7^a by means of screw threads 7^c. This feature of construction is to enable the body portion to be constructed practically from the standpoint of large production, it being easier to form 105 the head 7^b by drawing it in the well known manner and forming portion 7^a by milling the slots 10 straight through from one end to the other, than to form the body of a single piece and then mill the slots therein. 110 However, to vary the construction for the purpose of adapting it to economical meth-

ods of production in large quantities, does not necessitate a departure from the spirit and scope of my invention.

In the operation of my improved projectile the parts are brought to the position disclosed in Fig. 2 in which plunger 21 is in engagement with the inner edges of lugs 16 to hold the parts in their folded positions. These positions cause spring 17 to be compressed. As soon as the charge of explosive behind the projectile is exploded, the force of the explosion pushes spindle 20 of plunger 21 inwardly to cause it to occupy the position disclosed in Fig. 3. This frees the blades or arms 9 so that instantly upon the projectile's leaving the muzzle of the gun, the blades will be expanded by spring 17 to the positions disclosed in Fig. 3. The projectile will then be sent through the air with substantially no increased resistance and yet will have a materially increased range of destructiveness because of the expanse occupied by the blades when in their expanded positions. In firing at periscopes of submarines, at guy wires of air craft, and antenna of wireless apparatus, the small diameter of such targets, renders the chances of hitting them with ordinary projectiles small and likewise increases the probability of a bullet's ricochetting. The added size of my projectile multiplies the chances of hitting such targets, and likewise overcomes the tendency of the projectile's ricochetting.

The woven wire meshes of which fighting masts upon ships are composed, and likewise the ordinary wire entanglements, are little affected by an ordinary projectile, the former because the holes made by the projectiles are too small to materially affect the strength of the masts, and the latter because of the probabilities of the projectile's ricochetting. Applicant's projectile effectively destroys the fighting masts, because of the size of the holes which it tears therein, and the tendency of ricochetting upon wire entanglements is obviated by it.

In the form of construction disclosed in Fig. 1 the blades 9^a normally tend to expand. In this form plunger 21 and guide sleeve 19 of cap 18, illustrated in Figs. 2 and 3, are eliminated, and the normal tendency of the blades to expand from their folded positions, is overcome by extending the edges of shell casing 8 over the inner ends of the folded blades. In such a construction when the force of the explosion causes the projectile to be discharged from the shell casing 8, the blades are released so that they expand as soon as the projectile leaves the gun.

I prefer to have the blade formed as shown in Fig. 6 so that the angle between

the sides of the blade is the same as the angle of the rifling of the gun, so as to lessen the friction of the air upon the blade.

65

Having thus described my invention, what I claim is:

1. A projectile consisting of a body portion having a series of longitudinally extending slots, a series of arms located wholly within the slots, and pivotally mounted at one end to swing outwardly therefrom, a single spring engaging the ends of the arms, adapted to throw the arms to extended positions when released, and a trigger engaging the ends of the arms, adapted to release the arms to swing in response to the pressure of the spring when the propelling charge of the projectile is exploded.

2. A projectile consisting of a body having a series of longitudinally extending slots, a series of arms pivotally mounted at one end in the slots, a coil spring engaging the ends of the arms at different points of its periphery, adapted to swing the arms from the slots to an extended position with relation to the body, and a trigger engaging the ends of the arms, adapted to be operated to release the arms to permit movement thereof in response to the action of the spring.

80

3. A projectile consisting of a body portion having a series of longitudinally extending slots, a series of arms located wholly within the slots, pins located at the ends of the arms and mounted within a groove formed within the body portion, means for retaining the pins within the groove, a spring adapted normally to move the arms to extended positions, and means operative under impulse of the explosion of the propelling charge of the projectile, adapted to release the arms to permit them to move to their expanded positions.

90

4. A projectile consisting of a body having a series of longitudinally extending slots, a series of arms located within the slots, a pivot pin mounted upon each arm, a collar adapted to retain the pivot pin within the body to pivotally mount the arms therein, a spring normally tending to move the arms to expanded positions with relation to the body, and a trigger operative in response to the explosive pressure of the propelling charge of the projectile and adapted to release the arms to permit them to move to their expanded positions in response to the action of the spring.

105

In testimony whereof, I have hereunto subscribed my name this 7th day of May, 1917.

FREDERICK M. ROSS.
